UNITED STATES PATENT OFFICE

JACOB B. KLINE, OF THURMAN, IOWA.

DISH-WASHING MACHINE.

1,323,989.

Specification of Letters Patent. Patented Dec. 2, 1919.

Application filed August 29, 1918, Serial No. 251,947. Renewed May 16, 1919. Serial No. 297,560.

To all whom it may concern:

Be it known that I, JACOB B. KLINE, citizen of the United States, residing at Thurman, Iowa, in the county of Fremont and 5 State of Iowa, have invented certain new and useful Improvements in Dish-Washing Machines; and I do hereby declare the following to be a full, clear, and exact description of the invention, such as will enable 10 others skilled in the art to which it appertains to make and use the same.

This invention relates to a dish washing machine and particularly to a construction in which a spray of water is thrown upward 15 and inward upon the dishes contained within the open basket thereof.

This invention has for an object to provide a novel and improved construction of dish washing machine comprising a tank or receptacle having at its lower portion horizontally disposed pumping cylinders from which spray pipes extend, together with an open dish basket resting upon said cylinders, and means for operating the pump 25 pistons of said cylinders.

Another object of the invention is to provide a novel and improved construction of water pumping cylinders comprising parallel solid cylinders from which side spray 30 pipes extend upwardly, and an intermediate perforated cylinder closed at its opposite ends and having a piston therein to effect an upward spray of the water therefrom.

Other and further objects and advantages 35 of the invention will be hereinafter set forth and the novel features thereof defined by the appended claims.

In the drawings:

Figure 1 is a top plan of the machine; 40 Fig. 2 a cross section on line 2-2 of Fig. 1;

Fig. 3 is a plan of the pumping cylinders with the basket removed; and

Fig. 4 is a vertical longitudinal section 45 through the machine.

Like numerals of reference refer to like parts in the several figures of the drawing.

The numeral 10 designates the tank or receptacle which may be of any desired construction or configuration, preferably the shape of an ordinary wash boiler and the bottom 11 thereof is inclined toward the center and also toward one end as indicated at 12 so as to drain the contents to the outlet 55 which may be controlled by any desired means, for instance the spigot 13. This

tank is adapted to rest upon a stove or other heating medium or if desired may be supported upon a rest or stand 14 having depending legs 15 and edge flange or seat 60 16 adapted to receive the bottom flange 17 of the tank and retain the parts in proper position.

Removably seated within the tank is the pumping mechanism which in the present 65 instance comprises a novel construction and arrangement of parts. The solid pumping cylinders 18 are similar in construction and disposed parallel to each other at each side of the tank, while intermediate of these solid 70 cylinders a perforated spraying cylinder 19 is arranged, these several parts being removably supported in any desired manner, for instance by means of brackets 20 secured to the walls of the tank 10. Each of the 75 solid cylinders is provided between its center and outer ends with inlet valves 21 of any ordinary construction. Each of the solid cylinders 18 has extended upward therefrom two spray pipes 22 which are 80 connected to the opposite ends of the cylinder and extend longitudinally of the tank at the side wall thereof. This pipe is provided with any desired number of outlet apertures 23 adapted to throw the water upward and inwardly into the body of the tank. The cylinders 18 are also provided with solid pistons 24 adapted to reciprocate 85 therein at opposite sides of the center of the length of the cylinder, and these pistons are 90 connected to a cross head 25 by means of a connecting bolt 26 extending through a longitudinal slot 27 in the side wall of the cylinder. To prevent escape of liquid this slot is covered by a movable plate 28 which 95 travels with the cross head. The construction of the piston in each of the cylinders 18 is similar so that only one need be described.

The cylinder 19 is provided upon its upper surface with a series of perforations 29 and has disposed therein a centrally located piston 30 which is of greater longitudinal length than the pistons 24 and serves to balance and guide them. The piston 30 is connected to its driving means by means of 105 a pivot plate 31, formed as part of cross head 25, through which securing bolts 32 extend into the piston, and these bolts also carry a plate 33 covering the slot 34 in the bottom of the piston 19 within which the 110 connecting means travel.

Any desired means may be used for driv-

ing or reciprocating these pistons, a preferable form thereof being herein shown and comprising a pitman 35 connected with the plate 31 at 36 and pivoted at its opposite end 37 to the crank wheel 38. This wheel is disposed at the lower end of the shaft 39 and passes through the end of the cylinder 19 so as to secure a bearing 40 therein and to be removable therewith. The upper end of this shaft extends through the bearing bracket 41 and is provided with a bevel gear 42 which meshes with a coöperating gear 43 mounted in the bearing 44 of the bracket. The shaft 45 from the gear 43 is also mounted in a bearing bracket 46 and provided with an operating handle 47 as shown in Fig. 4, and bearing brackets 41 and 46 are secured to an end wall of the tank 10 by any desired means, such as bolts 48.

20 The dishes or other articles to be washed are introduced into the tank in any desired form of basket, for instance the removable wire construction 50 as shown. This form is provided at its ends with hand holds 51 and upon its bottom with concave seats 52 adapted to rest upon the cylinders of the pumping mechanism. The end of the basket next to the driving mechanism is provided with a recessed portion 53 adapted to fit 30 around these parts and protect them from contact by the basket or articles therein.

In the operation of the invention the operation of the crank arm produces a reciprocation of the pistons in the central portion 35 of the several cylinders which produces an upward jet or spray of water from the perforated cylinder. The solid cylinders intake through the valves 21 and discharge from their opposite ends through the spray 40 pipes 22 extending along the sides of the tank so as to effect an upward and inward spray upon the dishes or other articles within the basket and effects a thorough cleaning of the same. After the initial 45 washing operation with hot water and soap the suds may be withdrawn and fresh water introduced to effect a similar thorough rinsing of the dishes. After the final withdrawal of the water the dishes may be removed from the tank or allowed to drain 50 therein until dry. The construction and arrangements of the parts confines the pumping mechanism entirely to the bottom of the tank beneath the dish basket and permits the convenient removal of the several 55 parts for the purpose of cleaning or their easy replacement. The arrangement of the pistons and their driving mechanism produces a simple and effective connection for 60 pumping the water from the bottom of the tank and spraying it upon the articles to be cleansed.

While I have specifically illustrated a desirable construction and configuration of 65 the several parts of this machine still the

invention is not confined thereto as the novelty thereof is defined by the following claims.

What I claim is:

1. In a dish washing machine, a tank, 70 parallel pumping cylinders disposed at the lower portion thereof and provided with pistons, driving mechanism for reciprocating said pistons, and spray pipes extending upward from the opposite ends of said pumping cylinders and longitudinally therewith.

2. In a dish washing machine, a tank, parallel pumping cylinders disposed at the lower portion thereof and provided with 80 pistons, driving mechanism for reciprocating said pistons, spray pipes extending upward from the opposite ends of said pumping cylinders and longitudinally therewith, and a central perforated cylinder provided 85 with a piston connected with said pumping mechanism.

3. In a dish washing machine, a tank, parallel cylinders disposed at the lower portion thereof and provided with pistons therein, 90 spray pipes extending from the opposite ends of said cylinders, a central cylinder having a perforated upper wall and a piston disposed therein, an open basket disposed within the tank and resting upon said cylinders, and means for operating the pistons of 95 said cylinders simultaneously.

4. In a dish washing machine, a tank, parallel cylinders disposed at the lower portion thereof and provided with pistons therein, 100 spray pipes extending from the opposite ends of said cylinders, a central cylinder having a perforated upper wall and a piston disposed therein, an open basket disposed within the tank and resting upon said cylinders, driving connections from said pistons extending through slots in the walls of said cylinders, a cross head from which said connections extend, cover plates for said slots carried by said cross head, and a driving connection for said cross head. 105

5. In a dish washing machine, a tank, cylinders therein provided with pistons, means extending from said cylinders for spraying water upon the dishes, a cross head connecting said pistons, a pitman pivotally connected to said cross head, a vertically disposed shaft at one end of the tank provided at its lower end with a crank wheel pivoted to said pitman, a bevel gear at the upper end of said shaft, and a coöperating bevel gear carried by a driving shaft. 115

6. In a dish washing machine, a tank, parallel cylinders disposed at the lower portion thereof and provided with pistons, a central perforated cylinder provided with a piston of greater length than the pistons in the closed cylinders, a cross head connecting the several pistons, means for reciprocating said cross head, an open basket adapted to be 120 125 130

disposed within the tank above said pistons, and spray pipes extending from said first named cylinders along the sides of the basket.

5 7. In a dish washing machine, a tank, a series of cylinders disposed at the lower portion of said tank, means connected with said cylinders for spraying water upon the dishes, pumping means connected with said 10 cylinders and an open dish basket having concave portions upon its under surface to fit upon said cylinders.

8. In a dish washing machine, a tank, a series of cylinders disposed at the lower 15 portion of said tank, means connected with

said cylinders for spraying water upon the dishes, pumping means connected with said cylinders, an open dish basket having concave portions upon its under surface to fit upon said cylinders, and a driving mechanism at one end of said tank connected to said pumping mechanism by a pitman disposed beneath said cylinders.

In testimony whereof I have signed my name to this specification in the presence of 25 two subscribing witnesses.

JACOB B. KLINE.
